CASE

Frank W. Johnson, South Pasadena, and Harold H. Patterson, Los Angeles, Calif.

Application July 29, 1932, Serial No. 626,193

1 Claim. (Cl. 206—72)

This invention relates to cases of the type adapted to hold chips.

The invention has for an object the provision of a case for holding chips which is compact, 5 easily carried, maintains the chips in a definite order without fear of shifting, and which has certain parts so arranged that the chips may be readily moved to a given position within the case when the case is open so that the chips may 10 be readily contacted.

The invention contemplates a carrying case within which are one or more trays, the trays being adapted to hold chips of different denominations, and which tray or trays are movable 15 to position the same at a convenient angle so that the chips may be readily removed from the tray or trays.

A further object of the invention is the provision of a case adapted to hold one or more trays in such a manner that chips are prevented from 20 accidental dislodgment from the tray so as to fall beneath the tray and render recovery thereof difficult.

The invention has for a further object the provision of a case for holding chips or the like, 25 which is simple of construction, inexpensive in cost of manufacture, and generally superior to devices now known to the inventors.

With the above and other objects in view, the 30 invention consists in the novel and useful provision, formation, construction, association, and relative arrangement of parts, members and features, all as shown in a certain embodiment in the accompanying drawing, described generally, 35 and more particularly pointed out in the claims.

In the drawing:

Figure 1 is a perspective view of the chip case, 35 the cover being removed.

Figure 2 is a longitudinal sectional view of the 40 case, the cover being in position.

Figure 3 is a cross sectional view on the line 3—3 of Figure 1, and,

Figure 4 is a fragmentary transverse sectional 45 view on the line 4—4 of Figure 3, with chips within certain of the trays.

Referring now with particularity to the drawing, the improved chip case is designated as an 50 entirety by 1 and the same includes a case or box 2, having end members 3 and 4, side members 5 and 6, and a base 7, all said members being held in position of aggroupment in any convenient manner. The end members, constituting the top and bottom portions of the case, are both provided with ledges 8 and 9 and the 55 side members 5 and 6 correspond in height to

the height of the said ledges. This construction readily accommodates a cover 10 which rests upon the ledges and overlies the tops of the side members, as shown in Figure 2. To this end, the end member 3 may be provided with one 5 or more transverse openings, such as indicated at 11, adapted to receive one or more pins 12 projecting from the end of the top 10. The top adjacent the opposite end thereof is formed with a channel 13 adapted to confine a pull bolt 14, 10 which bolt is adapted to be received within an opening 15 in the top 4, whereby the cover is held locked to the case.

Within the case are adapted to be confined one or more trays and in the present instance 15 two trays are shown and designated as 16 and 17. The trays may be of the same length or one tray may be of greater length than the other, the size of the trays and the number thereof being optional and depending upon the size of the 20 case. In the present instance, the tray 17 is of greater length than the tray 16 and both trays are of the same width. The trays, however, are of identical construction, although within the purview of our invention and the scope of the 25 claim, we reserve the right to change the general configuration thereof. Both trays are provided with one or more elongated transversely curved grooves 18 of a size best adapted to hold a chip or chips, as shown in Figure 4, the chips being 30 designated as 19. The said trays may be of solid block formation with the elongated grooves cut therein, or the chip receiving grooves may be formed within a block secured to a framing. In the present instance, the chip receiving grooves 35 are formed in a block and fitted within a framing, as follows:

The tray 16 is provided with a base 20, and end wall 21 and a pair of side walls 22 and 23. The end wall 21 is of greater height than the side 40 walls. This construction is followed for the tray 17, with the exception that one end of the side walls is angled relative to the base, as shown at 24; otherwise, the same reference numerals will apply to this tray. The chip receiving member 45 constitutes a block 25 formed with the transversely curved grooves 18, and this block is fitted against the end wall 21 and between the side walls 22 and 23 and held therebetween by any suitable means.

Operating mechanism designated generally as 50 26 is provided for moving the trays from a position paralleling the base 7, as shown in Figure 2, to an angle relative to said base, as shown in Figure 3. This mechanism includes a pair of 55

rods 27, one adjacent each side of the case, one end of which rods are interconnected by a cross-bar 28. Centrally extending from the cross-bar 28 is a pull lever 29. This pull lever is passed through a slot 30 in the top 1. Links are provided for both sides of the trays, as shown in Figures 2 and 3, the links being designated as 31. One end of a link is pivotally secured to a side of the tray while the opposite end is pivotally secured to a rod 27. Transversely extending between sides of the case are blocks 32 and 33. The block 33 is transversely bored to accommodate passage therethrough of the rods 27, and this block likewise acts to guide movement of said rods. The end wall 21 of the tray 16 carries a hinge 34 adjacent the base 20 and this hinge has one leaf secured to the top surface of the block 32. The tray 17 is likewise provided with a hinge 35 in the same location as for the tray 16 with one leaf thereof secured to the top surface of the transverse block 33. In order to guide movement of the pull lever 29, I have provided a small block 36 formed with a slot in alignment with the slot 30, the pull lever being passed through the slot in the block, as best shown in Figure 3. The inner surface of the end 4 is inclined or progressively increases in transverse thickness, as shown at 37. The inner surface may be curved to correspond to the radius of curvature defined when the tray 17 is moved relative to its hinge point. The ends 24 of the tray are so curved as to normally conform to the curvature of this inner surface 27.

It is apparent that the operating mechanism 26 for the trays may be modified by placing a rod 27 centrally of the box 2 with the links 31 attached to the bases of the trays midway between the sides thereof. This would simplify the construction and avoid duplication of mechanism, the pull lever 29 being directly secured to the rod 27 or forming a part thereof.

The operation, uses and advantages of the invention just described are as follows:

Upon removing the cover 10 from the case, a pull upon the lever 29 will project the trays outwardly from the position shown in Figure 2 to that shown in Figure 1. As this lever is moved, the rods 27 are correspondingly moved to in turn swing the links 31 from the position shown in Figure 2 to that of Figure 3. These links raise the trays relative to their hinged positions with the extended end 21 of the tray 16 abutting against the inner surface of the end 3 of the tray and the extended end 21 of the tray 17 abutting against the upper end of the tray 16. The movement is such that the links 31 move slightly beyond a center position so that the trays are

maintained in the inclined position without fear of dropping unless the lever 29 is forcibly pushed inwardly to move the links. When chips are placed within the chip receiving channels, said channels beneath the trays, due to the close fit that exists between the said trays. It will be noted that the end 24 of the tray 17 has a close fit engagement with the inner surface of the end 4 of the case, and that the extended end of the tray 17 by reason of its abutment against the end of the tray 16, prevents the likelihood of any chips falling between the trays at this zone. Furthermore, chips are prevented from falling into the case adjacent the hinge 34 by reason of the extended end 21 of the tray 16 engaging the inner surface of the end 3 of the case. The construction is such that the chip case may be relatively shallow and still provide for a considerable tip, if desired, for the trays. This is the result of providing a constantly changing radius of movement for the links in their engagement between the rods and the trays, considering the pivot points for the trays.

When the trays are lying flat within the case, the chips may be positioned therein in accordance with their denominations and when the cover is placed upon the case, it is apparent from the showing of Figure 2, the height of the chips being indicated by dotted lines at 38, that said chips are held in position. The case is easily carried and as the construction is simple, the chip case may be manufactured at little expense.

It is obvious that various changes and modifications and variations may be made in practicing the invention in departure from the particular showing of the drawing without departing from the true spirit of the invention, as defined by the scope of the appended claim.

We claim:

In a device of the character disclosed, a case, a chip tray hinged at its rear end to the base of said case to swing completely into the case or to swing outwardly of the case into a position with its forward end above the case, said tray being formed with longitudinal channels for holding chips, a pull rod mounted in said case, a link connected to said pull rod and to said tray, and an actuating member connected to said pull rod and extending through the front end of said case for pulling said rod forwardly or pushing it rearwardly for swinging said tray through the medium of said link, outwardly or inwardly of said case.
